Primary Examiner — Mehri F Bajoul

(74) Attorney, Agent, or Firm — Banner & Witcoff, Ltd.

(57) **CLAIM**

The ornamental design for an electronic console, as shown and described.

DESCRIPTION

FIG. 1 is a front perspective view of an electronic console showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear bottom perspective view thereof.

The broken lines depicting features of the electronic console in FIGS. 1-8 form no part of the claimed design.

1 Claim, 8 Drawing Sheets(56)
